UNITED STATES PATENT OFFICE.

OSCAR D. MAY, OF OAK PARK, AND JOHN H. MALONE, OF CHICAGO, ILLINOIS.

DESIGN FOR A BADGE.

53,312.

Specification for Design.

Patented May 13, 1919.

Application filed January 29, 1919. Serial No. 273,923. Term of patent 7 years.

To all whom it may concern:

Be it known that we, OSCAR D. MAY and JOHN H. MALONE, both citizens of the United States, residing at Oak Park, in the county of Cook and State of Illinois, and Chicago, in the county of Cook and State of Illinois, respectively, have invented a new, original, and ornamental Design for a Badge, of which the following is a specification, reference being had to the accompanying drawing, forming a part thereof.

In the drawing, the figure is a face view of the badge embodying our new design.

We claim:

The ornamental design for a badge, as shown.

OSCAR D. MAY.
JOHN H. MALONE.

Witnesses:

MILDRED STUMPF,
KATHARINE GERLACH.
